AUTOMATIC TELEPHONE SYSTEM

Application filed November 26, 1926, Serial No. 150,911, and in Germany January 5, 1926.

In large telephone systems with automatic working comprising several exchanges difficulties occur when all the junction lines outgoing in a certain traffic direction from the calling exchange are unavailable and it is necessary to deviate the connections to the wanted exchange over other junction routes.

For this purpose a number of junction lines could be rendered available in the group of junction lines going to the exchange, over which the connections can be deviated, and the incoming end of these junction lines could be directly connected to junction lines going to the wanted exchange, which is not accessible to the calling exchange over a direct route. Such an arrangement renders it necessary to divide the group of junction lines, but it is known that this would have a bad effect on the traffic carrying capacity of the junction lines and thus on the efficiency of the installation.

Considerable difficulties also occur when connections are deviated over the junction lines used for calls between the calling exchange and the exchange used as an intermediate exchange for the deviated connections, because these junction lines terminate at switches of a group selecting stage located in the building up of the connection beyond the group selecting stage, which determines the traffic direction and therefore selects the exchange.

Arrangements are already known whereby the junction lines, which are used for the traffic between two exchanges are also used for the deviated connections. For this purpose in the exchanges, over which the deviated connections pass, is repeated the group selecting stage that determines the traffic direction, and this entails the provision of special devices for positioning these switches, because the calling party only transmits the trains of impulses required for the normal connecting route.

Now the object of the present invention is to enable connections to be deviated without reducing the efficiency of the group of junction lines to the exchange used as an intermediate exchange for the deviated connections and without repeating the group selecting

stage. According to the invention this is achieved by automatically connecting by means of hunting switches the junction lines, seized for deviated connections, to the junction lines outgoing in the desired traffic direction. 55

According to the invention the arrangement can be so devised that the junction lines, which are used for deviated connections, are provided with two differently numbered means of access, and the selection of one of these means of access determines whether it is to be used for a deviated call or a direct call. The incoming ends of these junction lines can be provided with two switches connected in parallel, namely a switch for making a numerical and then a non-numerical selection and another switch making only a non-numerical selection. Each of these switches so corresponds to a particular means 65 of access to the junction line that when one means of access is taken into use only the switch making a numerical and then a non-numerical selection is started up for setting up a connection in this exchange and when 75 the other means of access is taken into use only the non-numerical switch is started up for setting up a deviated connection.

However, the incoming end of the junction lines to be used for deviated connections can 80 be provided with only one switch, which, according to the particular means of access used, is positioned either by a numerical selection followed by a non-numerical selection 85 of a non-numerical selection only.

When separate switches are used for each traffic direction it is not necessary to connect these switches direct to the incoming end of the junction line, so that the switch, which is not required for setting up a connection, is 90 lying idle, on the contrary by means of call seekers can be connected up to the incoming end of the junction line a switch that is to be used for the connection to be set up.

The drawings show by way of example several methods of carrying out the invention. 95

The Figure 1 shows the arrangement according to the invention applied to a telephone area having three exchanges VSt I, VSt II and VSt III. 100

The Figure 2 shows an arrangement for connecting the junction lines to the numerical switches of the calling exchange.

The Figures 3-8 show different methods of carrying out the invention, of these the Figure 3 shows an arrangement, in which the junction lines to be used for deviated connections are provided with different auxiliary leads associated with the differently numbered means of access.

10 The Figure 4 shows an arrangement having one auxiliary lead common to all the differently numbered means of access to the junction line.

15 The Figure 5 shows the application of the invention to two wire junction lines.

The Figure 7 shows an arrangement, in which the incoming ends of the junction lines to be used for the deviated connection have 20 access to several groups of call seekers and a call seeker belonging to a particular group is started up according to the connection to be set up.

25 The Figure 8 shows an example, in which the incoming end of the junction line is provided with a switch which is positioned either by a numerical selection followed by a non-numerical one or is positioned only by a non-numerical selection.

30 The main features of the invention will now be described with reference to Figure 1.

If the subscriber T_{ln1} wishes to set up a connection with the subscriber T_{ln3} connected to the exchange VSt II, the first 35 group selector $I.GW1$ is positioned onto the contact group $DK2$ and an idle junction line $VL1$ to the exchange VSt II is seized, at which the numerical switches $II.GW2$ and $LW2$ are positioned.

40 Now it will be assumed that all junction lines between the exchanges VSt I and VSt II are marked engaged for some reason or other. In order nevertheless to be able to set up connections between the subscribers of the exchange VSt I and those of the exchange VSt II, a connection between the terminals 1 and 2 is removed at the intermediate distributing frame, and in place thereof the terminal 1 is connected with the terminals 3. By means of 45 this switching operation, the junction lines $VL2$, which are connected to the third contact group $DK3$ and go to the exchange VSt III, are also connected in parallel to the second contact group $DK2$ and the connection 50 between this contact group and the line group $VL2$ is provided with two switches $II.GW3$ and MW located in parallel in the example shown in the Figure 1. When a call is to be made to a subscriber of the exchange VSt III 55 and for this purpose the $I.GW1$ is set onto the contact group $DK3$, only the group selector $II.GW3$ is started up and positioned in the manner hereafter explained, while the hunting switch MW is not affected by this call.

60 On the other hand, when a call is to be set up 65 to a subscriber of the exchange VSt II, the switching operation effected at the distributing frame, prevents a junction line going directly in the desired traffic direction to be seized after the first group selector $I.GW1$ has been positioned on the second contact group $DK2$, and a junction $VL2$ going to the exchange VSt III is seized. The connection is deviated over this junction line $VL2$ and the exchange VSt III. As the first group 70 selector $I.GW1$ has been set on the contact group $DK2$ instead of on the contact group $DK3$, the hunting switch MW is started up and it hunts for a junction line $VL3$ going to the exchange VSt II. For this connection 75 the parallelly located switch $II.GW3$ cannot be operated for the reasons explained hereafter. At the exchange VSt II a second group selector $II.GW4$ and a final selector $LW2$ are positioned over the junction line 80 $VL3$; the deviated connection over the exchange VSt III then extends over the following junction lines and connecting devices: subscriber T_{ln1} , $VW1$, $I.GW1$, $VL2$, MW , $VL3$, $II.GW4$, $LW2$, T_{ln3} .

85 In the Figure 1 is indicated an arrangement, in which the deviation of connections over another exchange is dependent on a switching operation performed by the exchange staff, who connect at a distributing frame the junction lines, which are to be used for the deviated connections, in parallel at that contact group, which has the junction lines marked engaged.

90 Now the Figure 2 shows an arrangement, in which the deviation of the connections is effected automatically. Here likewise the contact group $DK2$ is provided for calls to the exchange VSt II, while over the contact group $DK3$ are set up connections to the exchange VSt III. The junction lines $VL1$ going to the exchange VSt II are connected to the first five contacts of the contact group $DK2$. When all these lines are marked engaged, the switch $I.GW1$ automatically reaches the succeeding contacts, to which are likewise connected the junction lines that are connected to the first contacts of the contact group $DK3$. Hence when the switch $I.GW1$ does not find an idle line in the group $VL1$, 105 it automatically seizes an idle junction line in the group $VL2$ without the assistance of the exchange staff, thus the connection is automatically deviated.

110 In Figure 3 is shown by way of example an arrangement in which the trunk lines $VL2$, which are to be used for deviated connections, are provided with a separate auxiliary lead for each means of access.

115 When a call is to be set up to a subscriber of the exchange VSt III, the wipers 3, 4 and 5 of the switch $I.GW1$ are positioned on the contacts 6, 7 and 8 of the contact group $DK3$. Thereby the following circuit is established: earth, test relay $P1$, wiper 5, contact 8, lead 120 125 130

VL2c, contact 14c2, relay C1, battery, earth. The relays P1 and C1 are operated. The relay P1 at the contacts 12p1 and 13p1 switches through the speaking leads, while the relay C1 at contact 15c1 disconnects the relay C2 and battery from the lead VL2d and thus marks engaged the junction line VL2 in the second contact group DK2. This junction line cannot be seized over the contacts 9, 10 and 11 of the contact group DK2, because when a test wiper reaches the test contact 11 no test circuit is closed.

At the incoming end of the junction line VL2 the relay C1 in the exchange VSt III initiates in any desired manner the positioning of the switch II.GW3, which is to be next positioned by number impulses from the calling party.

When the junction line is seized by the first group selector I.GW1 for a deviated connection over the contacts 9, 10 and 11 in the contact row DK2, the relay P1 is energized in series with the relay C2 at the incoming end of the junction line. The relay P1 again connects through the speaking leads, while the relay C2 marks engaged the junction line in the third contact group DK3, because by opening the contact 14c2 it disconnects the relay C1 from the lead VL2c. But the relay C2 also opens its contacts 16c2 and 17c2, thereby disconnecting the speaking leads VL2a and VL2b from the leads going to the wipers 18 and 19 of the second group selector II.GW3 and connecting its speaking leads over the contacts 20c2 and 21c2 to the leads 22 and 23, which only go to the non-numerical switch MW.

At its contact 24c2 the relay C2 closes the following circuit of the motor magnet D1 of the switch MW: earth, contacts 24c2, 25p2, self interrupting contact 26d1, motor magnet D1, battery, earth. The switch MW is moved on step by step over its bank contacts and is arrested when it reaches an idle junction line VL3 going to the exchange VSt II (see Fig. 1), because the following test circuit is then established: earth, contact 27c2, windings I and II of relay P2, wiper 28, contact 29, relay C3, battery, earth. The relay P2 at its contact 25p2 opens the circuit of the motor magnet D1, it marks engaged the selected junction line VL3 by short circuiting its high resistance winding I at contact 30p2, and at the contacts 31p2 and 32p2 it switches through the leads 22 and 23 and with them the speaking leads VL2a and VL2b of the junction line VL2 to the wipers 33 and 34 of the switch MW, hence the speaking leads are now connected over the contacts 35 and 36 to the speaking leads 37 and 38 of the junction line VL3.

In the Figure 4 is shown an arrangement with the three wire junction lines VL2. They consist of the two speaking leads and a single auxiliary lead VL2c' for the two means of

access. The Figure 4 only shows the auxiliary lead VL2c'.

The junction line VL2 having been seized over the contact 40 of the contact group DK3, the following test circuit is then established: earth, test relay P3, wiper 41, contact 40, contact 42c4, lead VL2c', relay C5, relay C6, battery, earth. The relays P3 and C6 are operated in this circuit. The relay C6 at contact 43c6 at once short circuits the relay C5, which therefore cannot operate. The relay C6 now prepares the positioning of the switch II.GW3 associated with the junction line VL2. In any known manner the test relay P3 marks engaged the seized junction line.

During this connection it is impossible for the junction line to be seized over the second means of access (contact 44DK2) because when a hunting switch reaches the contact 44, its test relay does not receive enough current to operate it.

On the other hand when the junction line is seized over the contact 44 in the contact group DK2, the test circuit still contains the high resistance winding of relay C4. Hence the current flowing over the lead VL2c' is so weak that in addition to the test relay P3 only the relay C5 can be operated and not the relay C6. The relay C5 now connects up the switch MW and disconnects the switch II.GW3 in the same manner as the relay C2 in the arrangement shown in Fig. 3.

At the outgoing end of the lead VL2c' the relay C4 opens its contact 42c4 and so marks engaged in the contact group DK3 also the seized junction line.

The Figure 5 shows an example for two-wire junction lines VL2.

It will first be assumed that a two-wire junction line VL2 has been seized over the contact group DK3, which is the indication that a connection is to be set up with a subscriber of the exchange VSt III. After the wipers 50, 51 and 52 have been set on the contacts 53, 54 and 55, the following test circuit is established: earth, relay P3, test wiper 52, contact 55, contact 56c8, relay C7, battery, earth. The relay C7 marks the seized junction line engaged, so that it cannot be seized by a switch over the contact group DK2, as it opens the contact 90c7 and so disconnects the relay C8 from the test contact 91. Furthermore the relay C7 closes its contact 59c7 and so switches through the lower speaking lead of the junction line VL2. For the present no circuit changes are initiated at the incoming end of the junction line.

When the calling party transmits impulses for positioning the switch II.GW3, the impulses operate the relay A1 in the following circuit: earth and impulse contact at a preceding switch, which is not shown, wiper 50, contact 53, lead 60 of the junction line VL2, contacts 61c10, 62p4, relay A1, battery, earth.

The contact 63a1 repeats the impulses to the lifting magnet H1 of the switch II.GW3: earth, contacts 63a1, 64m1, shaft contact 65w, lifting magnet H1, battery, earth. At the first lifting step of the switch, the off-normal contact 66k is closed and thus the relay B1 is energized in the following circuit: battery at the preceding switch, which is not shown, wiper 51, contacts 54, 59c7, lead 67 of the junction line VL2, contact 94c10, relay B1, contact 66k, earth. The relay B1 opens its contact 68b1 and so prevents the rotary magnet D2 being connected up prematurely. At the functioning of the first impulse, the closing of the contact 69a1 energized the relay C9 as follows: earth, contacts 69a1, 70b1, relay C9, resistance 71, battery, earth. The relay C9 opens its contact 72c9 and prevents the release magnet M1 being energized after the contact 73k is closed when the first lifting step is taken. Furthermore by opening the contact 74c9 the relay C9 disconnects the relay C10 from the lead 67. The closing of the contacts 75c9 and 76c9 prepares the circuit of the rotary magnet D2 and the test circuit. The following locking circuit for the relay C9 is closed after the first lifting step: earth, battery, resistance 71, relay C9, off-normal contact 80k, earth. After the relay B1 has been energized, the relay C9 is short circuited over the contacts 69a1 and 81b1 each time the relay A1 is energized, but it cannot fall back, because it is rendered slow acting when its winding is short circuited and because the contact 69a1 is closed only momentarily. At the end of the train of impulses the relay B1 falls back owing to the steering circuit over the lead 67 being opened, and at its contacts 68b1 the relay closes the circuit of the rotary magnet D2: earth, contacts 82k, 83p4, 75c9, 68b1, 84a1, rotary magnet D2, battery, earth. In known manner the switch II.GW3 is moved step by step over the contacts in the selected group. When an idle line is found, the following test circuit is established: earth, winding I of relay P4, contact 76c9, winding II of relay P4, wiper 77, contact 85, resistance 86, battery, earth. The relay P4 is operated; by opening its contact 83p4 it inter-rupts the circuit of the rotary magnet D2, by closing its contact 87p4 which has already been earthed over the off-normal contact 88k, it marks the seized junction line engaged to other switches because it short circuits the high resistance winding I. Furthermore the speaking leads are switched through at the contacts 89p4 and 90p4, while at contact 62p4 the relay A1 is disconnected. The connection is completed in any desired manner by positioning the succeeding switches. At the end of the conversation the positioned switch II.GW3 is released by disconnecting earth from the relay P3 in any desired manner, which is of no interest here. The disconnection of earth now causes the re-

lease of the relays P3 and C7. Upon the release of the relay C7 the following circuit is closed for initiating the release of the switch II.GW3: earth, battery, relay F, contacts 92c8, 93c7, lead 67, contact 94c10, relay B1, contact 66k, earth. The relays F and B1 are operated. By closing its contact 94b1, the relay B1 connects the relay A1 to the lead 60, while the relay F, by closing its contact 95f, likewise connects earth to the lead 60; hence the following circuit is established for energizing the relay A1: earth, contact 95f, lead 60, contacts 61c10, 94b1, resistance 95, relay A1, battery, earth. The relays A1 and B1 close their contacts 69a1 and 81b1. The relay C9 now can fall back. It opens its contact 76c9 and closes its contact 96c9, thereby short circuiting the winding II of the relay P4. The relay P4 having been kept energized over this winding during the call, it now falls back; by opening the contact 87p4 it disconnects earth from the wiper 77 and at contact 97p4 it closes the circuit of the release magnet M1, which has been prepared at contact 72c9: earth, contacts 73k, 97p4, 72c9, release magnet M1, battery, earth. Upon operating, the release magnet M1 returns the switch II.GW3 to its normal position.

When the switch II.GW3 has returned to its normal position, the contact 66k is opened, thereby interrupting the circuit of the relays B1 and F. Both the relays fall back and open the contacts 94b1 and 95f, thus the relay A1 is also de-energized. Thus have been returned to their normal position all the switching means of the switch II.GW3 as well as the relays located at the outgoing end of the junction line.

It will now be assumed that the shown junction line VL2 is seized over the contact group DK2. The following test circuit is established after the wipers 50, 51 and 52 have been positioned on the contacts 100, 101 and 91: earth, relay P3, wiper 52, contacts 91, 90c7, relay C8, battery, earth. The relay C8 closes its contact 102c8, which is in parallel with the contact 90c7, furthermore at its contact 103c8 it connects up the relay C7. Before the relay C7 can operate and switch through the speaking lead and open the contact 93c7, the following circuit for energizing the relay C10 at the incoming end of the junction line has been closed: earth, contacts 104c8, 93c7, lead 67, contacts 94c10, 74c9, 105a1, relay C10, battery, earth. By closing its contact 106c10 the relay C10 locks itself in a holding circuit over the resistance 107 independent of the lead 67. The other switching operations performed by the relay C10 will be explained later on.

When the relay C8 was energized at the outgoing end of the junction line it marked the seized line engaged to switches over the contact group DK3, because it opens the con-

tact 56c8 and so disconnects the relay C7 from the test contact 55.

At the incoming end of the junction line VL2 the relay C10 is energized and opens the contacts 61c10 and 94c10, thereby disconnecting the leads, which go to the wipers of the switch II.GW3, from the speaking leads 60 and 67 of the junction line VL2, and it connects these leads over the contacts 108c10 and 109c10 to the leads 110 and 111, which go to the switch MW. The other switching operations cannot affect the switching means of the switch II.GW3. The relay C10 at contact 112c10 now closes the circuit of the 15 motor magnet D3 of the switch MW: earth, battery, contacts 112c10, 113p5, self interrupting contact 114d3, magnet D3, battery, earth. Furthermore the relay C10 at its contact 115c10 has connected the test relay P5 20 to the test wiper 116. When the wipers of the switch MW reach the contacts of an idle junction line VL3, the following circuit functions: earth, windings I and II of relay P5, contact 115c10, wiper 116, contact 117, resistance 118, battery, earth. The relay P5 is 25 operated and arrests the switch MW by opening the contact 113p5. The seized junction line is marked engaged, because the high resistance winding I is short circuited. Furthermore at the contacts 120p5 and 121p5 the speaking leads are switched through.

The connection is completed in any desired manner. At the end of the call is interrupted the circuit existing over the relays P3 and 35 C8 in the exchange VSt I. Both the relays fall back. The opening of the contact 103c8 also releases the relay C7, which upon its release initiates the release of the switch at the incoming end of the junction line, 40 because the following circuit functions over the lead 67: earth, battery, relay F, contacts 92c8, 93c7, lead 67, contact 109c10, lead 111, relay B2, earth. The relay B2 closes its contacts 122b2 and 123b2. The relay F closes its 45 contact 95f and so establishes the following circuit: earth, contact 95f, lead 60, contact 108c10, lead 110, contact 122b2, resistance 124, relay A2, battery, earth. The relay A2 closes its contact 125a2. Over the serially 50 connected contacts 123b2 and 125a2 the relay C10 is now short circuited and it falls back. Thereupon its contact 115c10 is opened, thus interrupting the circuit over the relay P5. The latter falls back. The 55 opening of the contacts 109c10 and 108c10 cause the circuits over the relays A2, B2 and F to be interrupted. These three relays fall back. All the switching devices of the junction line both at the incoming as well as at 60 the outgoing end have now been returned to their normal position.

In the examples shown in the Figures 3-5 there are two switches connected in parallel at the incoming end of the junction lines VL2, namely a switch for making a numeri-

cal followed by a non-numerical selection and a second switch making only a non-numerical selection. Now the Figures 6 and 7 show examples, in which two switches are not directly connected to the junction lines VL2. 70 In the arrangement shown in the Figure 6 the incoming end of the junction line VL2 has access to two groups of call seekers AS II and AS III. When the junction line VL2 is taken into use over the contact group 75 DK3, a switching operation is performed over the junction line VL2 for starting up the call seeker AS III. When such a call seeker has been positioned on the junction line VL2, the latter is connected with a group 80 selector II.GW3.

On the other hand when the junction line VL2 is taken into use over the contact group DK2, the switching operation performed when the junction line is taken into use, 85 causes the starting up of a call seeker AS II associated with an idle junction line VL3 and the switch now seeks the junction line VL2 taken into use.

The switching operation, which effects the 90 starting up of a call seeker in one of the two groups, also causes the junction line to be made ready for testing only in the contact field of the call seekers of the particular group, that is to say for example in the call seeker group AS III or in the call seeker group AS II.

In Figure 7 is shown an arrangement, in 95 which the wipers of the call seekers AS II are not directly connected to the junction line VL3, but the connection between the exchanges VSt III and VSt II is effected by a double non-numerical selection, because a call seeker AS II hunts for the seized junction line VL2 and an intermediate switch VW II associated with this call seeker hunts for an idle junction line VL3. 105

In a similar manner a group selector 110 II.GW3 is not directly associated with the call seeker AS III, and the connection between a seized junction line VL2 and an idle group selector II.GW3 is likewise set up by a double non-numerical selection, which is effected by the call seeker AS III and an intermediate switch VW III connected therewith. 115

The Figure 8 shows an arrangement, in 120 which a switch is associated with the incoming end of each junction line VL2, this switch being positioned either by a numerical selection followed by a non-numerical selection or is positioned only by a non-numerical selection. For example a Strowger switch can be used, which is provided with a special eleventh level. In their normal position, the wipers of this switch stand in front of this eleventh level, which is located below the first level used for the numerical selection. Hence when the rotary magnet instead of the lifting magnet is connected up immediately after 125

the switch has been taken into use, the wipers are at once rotated over this special level. If, on the contrary, the lifting magnet be first connected up, the switch will be operated in the known manner and the wipers will be raised by the lifting magnet to a level only accessible by a numerical selection, whereupon the wipers are positioned on a contact of the selected level by connecting up the rotary magnet.

10 The junction line $\sqrt{L}3$ going to the exchange VSII are connected to the special eleventh level, in front of which the switch wipers normally stand. Hence the rotary magnet has to be connected up at once if the 15 outgoing end of the junction line $VL2$, (which is not shown in Figure 8) be taken into use over the contact group $DK2$; while if the means of access connected to the contact group $DK3$ be used, the lifting magnet is first connected up for making a numerical selection and then the rotary magnet is connected up for making a non-numerical selection.

15 It will now be assumed that $VL2$ is a two wire junction line. Hence its outgoing end is similar to that shown in the Figure 5.

20 When the junction line is taken into use over the contact group $DK3$, the switch will be positioned in the same manner as that described with reference to Figure 5.

25 When the junction line at its outgoing end is taken into use over the contact group $DK2$, the relay $C12$ is first energized in the following route: earth, contact $104c8$, (Fig. 5) contact $93c7$, lead 67 , lead 131 (Fig. 8) contact $150c11$, relay $C12$, battery, earth. The relay $C12$ connects itself in a locking circuit over its contact $132c12$ and the resistance 133 . Over the contact $134c12$ it energizes the relay $C11$ and at contact $135c12$ it prepares the circuit of the rotary magnet $D4$. The relay $C11$ at contact $136c11$ closes the circuit of the rotary magnet $D4$: earth, contacts $135c12$, $137p6$, $136c11$, $138b3$, $139a3$, rotary magnet $D4$, battery, earth. Hence the wipers of the switch II.GW3 are at once moved over the contacts in the lowest (eleventh) level by the rotary magnet $D4$, and in known manner they hunt for an idle junction line $VL3$. The test circuit over the relay $P6$ has been prepared by the relay $C11$ at the contact $140c11$. At the end of the call the release of the switch is initiated as in Figure 5 by maintaining the relays $A3$ and $B3$ energized for some time. 30 The relays $A3$ and $B3$ at their contacts $141a3$ and $142b3$ short circuit the relay $C11$, and at their contacts $143a3$ and $144b3$ they short circuit the relay $C12$. Both relays fall back, because their windings remain short circuited for some time, and the release of the switch II.GW3 is thus brought about.

35 What is claimed is:

1. In a multioffice telephone system, three offices, trunks from the first office to the second office, trunks from the first office to the

third office, trunks from the second office to the third office, switching mechanism in the first office operative for extending a connection over one of said trunks to the third office, said switch mechanism further operative responsive to a busy condition of the trunks from the first to the third office to extend said connection to the second office by way of one of said trunks instead of to said third office, a non-numerical hunting switch in said second office, and means responsive to said last mentioned extension for automatically operating said switch to hunt for a trunk extending from the second office to the third office.

2. In a telephone system, a trunk terminating in one end in a numerical switch and a non-numerical hunting switch and at the other end in two branches, a switching mechanism having access to said branches, means whereby said mechanism is operated to seize said trunk from one of said branches to extend a connection, means responsive to a busy condition whereby said mechanism is operated to seize said trunk from the other of said branches to extend a connection, and means dependent upon the branch seized for determining whether said numerical switch or said non-numerical hunting switch is to be used for further extending said connections.

3. In a telephone system, a trunk terminating in one end in a numerical switch and a non-numerical hunting switch and at the other end in two branches, a switching mechanism having access to said branches, said trunk comprising a pair of talking conductors common to said branches, a test contact for each of said branches at said other end, means for operating said mechanism to seize said trunk over one of said branches to extend a connection, means responsive to a busy condition whereby said mechanism is operated to seize said trunk from the other of said branches to extend a connection, and means operated over the said test contact associated with the branch seized for determining whether said numerical switch or said non-numerical switch is to be used for further extending the connections.

4. In a telephone system, a trunk terminating in one end in a numerical switch and a non-numerical switch and in the other end in two branches, a switching mechanism having access to said branches, said trunk comprising only a pair of talking conductors common to both said branches, means for operating said mechanism to seize said trunk over one of said branches to extend a connection, means responsive to a busy condition whereby said mechanism is operated to seize said trunk from the other of said branches to extend a connection, and switching means operative in different ways according to the said branch taken into use for conditioning said numerical switch to be responsive to subse-

quent impulses or for automatically operating said non-numerical switch to further extend the connections.

5. In a telephone system, a trunk terminating in one end in a numerical switch and in the other end in two branches, a non-numerical switch associated with said numerical switch, a switching mechanism having access to said branches, means responsive to 10 a busy condition for operating said mechanism to seize said trunk over the first of said branches, and switching means operative responsive to said seizure for disconnecting said numerical switch from said trunk and 15 for connecting said non-numerical switch to said trunk.

6. In a telephone system, a two conductor trunk terminating in an automatic switch, a first and a second relay in said switch, means 20 for operating said switch to extend a connection, means whereby said first relay is energized over a circuit including one talking conductor of said trunk, means operative responsive to said energization for energizing 25 said second relay over a circuit including the other talking conductor of said trunk, and means responsive to the energization of said second relay for releasing said switch.

7. In a telephone system, a two conductor 30 trunk terminating in an automatic switch, a release and a test relay in said switch, means for operating said switch over said trunk to extend a connection, said relays being energized by the operation of said switch, means 35 controlled over the two conductors of said trunk for short circuiting said release relay thereby causing said relay to deenergize, contacts on said release relay closed responsive to said deenergization for short circuiting 40 said test relay thereby causing said relay to deenergize, and means controlled by said release and test relays for causing said switch to release.

8. In a telephone system, a two conductor 45 trunk terminating in a switch, means for operating said switch over said trunk to extend a connection, a pair of line relays in said switch, means controlled over said trunk for operating first one and then the other of said 50 line relays, a release and a test relay in said switch, means controlled by the operation of said line relays for causing the operation of said release relay; means controlled by the operation of said release relay for causing 55 the operation of said test relay, a release magnet in said switch, and means controlled by the operation of said release and test relays for operating said release magnet to release said switch.

9. In a multi-office telephone system wherein an automatic switch has access to alternative trunk routes for extending a connection to a third exchange and wherein the first route includes trunks comprising only two talking conductors directly connecting the

first and third exchanges while the alternative route includes trunks comprising only two talking conductors connecting the first and second exchanges and the second and third exchanges, means for operating said switch to directly select either of said routes by seizing a trunk to the third exchange or by seizing a trunk to the second exchange without seizing a trunk to the third exchange, and means in the second exchange automatically operated over said conductors in case the alternative route is taken into use for connecting the trunk in use extending from the first exchange to the second exchange with a trunk extending from the second exchange to the third exchange in order to complete the connection.

10. In a multi-office telephone system wherein an automatic switch in the first office has access to a group of trunk lines extending to a third office and to a group of trunk lines extending to a second office and wherein a group of trunk lines extend from the second office to the third office, means responsive to an encountered all trunk busy condition of the trunk lines extending from the first office to the third office for causing said switch to seize a trunk line extending to the second exchange, and automatic switching means comprising a non-numerical hunting switch in said second exchange responsive to said seizure for automatically extending the connection to the third exchange over a trunk line extending from the second to the third exchange.

11. In a multi-office telephone system wherein a switching mechanism in the first office has access to a group of trunks comprising only two talking conductors extending to a third office for extending connections thereto and to a group of trunks comprising only two talking conductors extending to a second office when all the trunks extending to the third office are busy and wherein a group of trunks extend from the second to the third offices, means for operating said mechanism to seize an idle trunk in either group to which it has access dependent upon their busy conditions in order to extend a connection to the third office, and a non-numerical hunting switch in the second office automatically operated over said conductors responsive to the seizure of a trunk extending from the first office to the second office for seizing a trunk extending from the second office to the third office in order to complete the connection.

In witness whereof, I hereunto subscribe my name this 28th day of October, A. D. 1926.

FRITZ LUBBERGER.

In witness whereof, I hereunto subscribe my name this 28th day of October, A. D. 1926.

MAX LANGER.
